(57) CLAIM

The ornamental design for a cup with an elevated drink opening, substantially as shown and described.

DESCRIPTION

FIG. 1 is a top perspective view of the cup lid of this invention; FIG. 2 is a top view of the cup lid of FIG. 1;

FIG. 3 is a bottom perspective view of the cup lid of FIG. 1;

FIG. 4 is a front view of the cup lid of FIG. 1;

FIG. 5 is a side view of the cup lid of FIG. 1, the opposite side view being a mirror image of that shown;

FIG. 6 is a rear view of the cup lid of FIG. 1; and,

FIG. 7 is a bottom view of the cup lid of FIG. 1.

The portions shown in broken lines are included to show environment and form no part of the claimed design.
